UNITED STATES PATENT OFFICE.

GEORGE A. HULL, OF CHICAGO, ILLINOIS, ASSIGNOR TO EQUIPMENT SPECIALTIES CO., OF CHICAGO, ILLINOIS, A CORPORATION OF ILLINOIS.

VENTILATING DOOR FOR THE HATCHWAYS OF REFRIGERATOR CARS.

Application filed December 11, 1924. Serial No. 755,202.

In the operation of railroad refrigerator cars it is customary practice in chilly or cold weather to dispense with ice in the ice compartment and to raise the hatchway covers leading to these ice compartments so that cold air can permeate around the perishable commodities and so that the breeze resulting from the motion of the car can blow down through the hatchways into the car. 10 The car is then said to be travelling "under ventilation." These open hatchways are an invitation to tramps to crawl down into the ice compartment and pilfer fruits or other commodities packed in the car. This is made possible because the bulk head which separates each ice compartment from the main compartment has openings at top and bottom for the circulation of cold air, and these 20 openings frequently afford accessibility to the commodities packed in the main compartment.

Theft-proof ventilating doors have heretofore been provided for these hatchways having spaced cross bars or other open-work construction to permit of a free circulation of air through the car, but the prior ventilating doors have generally been objectionable for numerous reasons. One objection is 30 that when these doors are in open positions they have to occupy space in the main compartment and hence they are apt to be jammed or injured in the packing of the main compartment. Also, because of the fact 35 that they have to slide into the main compartment, their movement into open position is often obstructed by the end of the door striking fruit crates or part of the cargo in the main compartment. These prior doors 40 have been locked in closed position at a point inside the main compartment, and, consequently, if it is desired to insert ice in the ice compartment as a result of change 45 of temperature in transit, access cannot be had to the point of locking for opening the door without first removing a considerable part of the cargo in the end of the car. These prior doors are also frequently injured in the packing of the ice into the ice compartment. 50

I have obviated these objections by providing a theft-proof ventilating door for hatchways which does not have to occupy space in the main compartment; also,

a door which can be locked or sealed from the top of the hatchway, so that the door lock or door seal is always accessible from the exterior of the car.

A further object is to provide adequate protection against injury to the door from the packing of ice into the ice compartment.

Referring to the accompanying drawings in which I have illustrated a preferred embodiment of my invention:

Figure 1 is a fragmentary sectional view taken longitudinally of the car through one of the hatchways;

Figure 2 is a plan view of the hatchway illustrating the ventilating door in closed position;

Figure 3 is a detail sectional view through the central pivot 28 such as on the plane 3-3, of Fig. 2, and

Figure 4 is a similar view through the outer sliding pivots 29 such as on the plane 4-4 of Figure 2.

Figure 1 illustrates the upper portion of a typical refrigerator car, the latter comprising the end wall 8, the side walls 9 and the roof 11. The side and end walls are of the usual heat insulating construction embodying several layers of hair felt with one or more air spaces intervening, no specific description of these details being necessary as they are points of construction well known in the art.

The ice compartment 12 is defined at each end of the car between the end wall 8 and an adjacent bulk head 13. The loading of the ice compartment is effected through two 90 hatchways 14, disposed on opposite sides of the central running board 15 which extends along the top of the car. It is through these hatchways that the cold air is circulated when the car is travelling under ventilation 95 and which it is desirable to protect by ventilating doors.

These hatchways are defined between spaced transverse headers 17 and 18 extending from side to side of the car for supporting the roof thereof. Said headers may form the front and rear sides of the hatchways or may have plates 19 and 21 secured thereto defining these hatchway walls. The inner and outer side walls of each hatchway 100 are formed by longitudinal plates or boards 22 extending between the transverse plates 19 and 21. The lower ends of the hatch-

way side plates 19, 21 and 22 terminate substantially flush with a false roof 24 extending longitudinally of the car below the main roof 11.

5 In the conventional construction of refrigerator cars the hatchways are set back from the adjacent end wall of the car so that there is a small space x between the end wall 8 and the adjacent edge of the hatchway 14 opening. It is this space that I propose utilizing for containing the door when the latter is moved into its open position. This space is generally of smaller cross dimension than the width of the hatchway, and, accordingly, it is desirable that the ventilating door be capable of folding or collapsing to be completely receivable in this space.

In the particular form chosen for exemplification the door is built up of a plurality of links 26 pivoted together in lazy tong relation. For obtaining the necessary rigidity these links may preferably consist of a series of long bars of angle section pivoted together with the flat upper and lower surfaces of opposing flanges contacting; that is to say, there is a lower series of links with their vertical flanges turned downwardly, and an upper series of links with their vertical flanges turned upwardly, the opposing surfaces of the horizontal flanges of both sets of links pivoting upon each other. The links may be joined along any number of lines of pivoting, Figure 2 illustrating five lines of pivoting a , $b-b'$ and $c-c'$.

25 The relatively stationary end of the door is suitably attached to a fixed channel 27 which is extended across the end wall 8 adjacent the false roof 24. The two end links terminating at the central line of pivoting a have pivotal mounting in the channel 27 on a fixed pivot 28. The two end links terminating adjacent the outer ends of the channel 27 have pivot pins 29 projecting upwardly and downwardly therefrom through 30 slots 31 cut in the top and bottom flanges of the channel 27. Small spacing sleeves 32 may be mounted on the shanks of the pins 28 between the horizontal flanges of the links and the inner walls of the channel 27 so as to maintain the links in erect position and prevent binding or play of the links on the pivot 28. Similar spacing sleeves 32 may be provided on the pin extensions 29 between the horizontal flanges of the links 26 and the spaced flange of the channel 27.

35 The sliding end of the door has similar attachment to a front sliding channel 34. The two end links terminating in the central line of pivots a , have pivotal mounting on a fixed pivot 28' carried by this front channel 34. The outer ends of the front links have slidable pivoted mounting through projecting pins 29' engaging in slots 31' in the channel, similarly to that just described of the stationary channel 27. Spacing sleeves

32 are also preferably provided on these pivots 28' and 29' for holding the ends of the links in proper relation in the channel.

The ends of the sliding channel 34 are guided in lateral guide channels 36 which 70 extend from the end wall 8 to a point substantially even with the rear edge of the hatchway and which are suitably secured to the false roof 24. These guide channels 36 are of considerable depth, so that the pivoted ends c of the links will project within the confines of these channels in all positions of the door. Thus, when the door is either completely opened or completely closed, the ends of these links will be braced by the 80 lower flanges of the guide channels 36, so that any weight placed upon the door when in its closed position will not bend the door downwardly or spring the links.

85 Any suitable locking or sealing means may be associated with the sliding channel 34 for locking or sealing the door in closed position. As exemplary of such a fitting, I have shown a short angle bar 38 projecting upwardly from the top of the front channel 90 34 and adapted to engage with a bracket 39 extending from the end walls 21 of the hatchway. The angle bar 38 and bracket 39 have cooperating apertures through 95 which a padlock or lead seal may be inserted for locking or sealing the door.

100 Where all four sides of the hatchway 14 extend down in substantial parallelism to the false roof 24, the guide channels 36 may both extend along the longitudinal edges of the hatchway, as indicated by the lower guide channel 36 in Figure 2. However, 105 a large number of refrigerator cars are now constructed to embody the new design of hatchway opening disclosed and claimed in United States Letters Patent No. 1,220,830, issued to William H. Emerick. This new design resides in flaring the inner side walls of both hatchways downwardly toward each other so that the portion of wall intervening 110 between the inner edges of the hatchways will be of substantially wedge-shaped section. When adapting the present ventilating door or grating to a car constructed in accordance with this design, the inner edge 115 of the door or grating must be extended substantially to the end of the inner sloping wall of the hatchway. This is represented in Figure 2 by the location of the upper channel 36 spaced inwardly from the vertical plane of the inner hatchway wall 22.

I claim:

1. In combination, a railroad car comprising a roof having a hatchway spaced from the adjacent end wall of the car, a door in position to move across the lower end of said hatchway, and guide means for said door extending from said hatchway to a point adjacent said end wall, whereby said door is movably supported to close said 120 door is movably supported to close said 125 door.

- hatchway or to lie wholly between said hatchway and the adjacent end wall of the car. 65
2. In combination, a railroad refrigerator car comprising a roof having a hatchway opening into the ice compartment, and a ventilating door for said hatchway adapted, when open, to occupy a position between said hatchway and the adjacent end wall of the car. 70
3. In combination, a railroad refrigerator car comprising a roof having a hatchway, and a sliding ventilating door for said hatchway adapted, in its open position, to occupy a space between said hatchway and the adjacent end wall of the car. 75
4. In combination, a railroad refrigerator car comprising a roof having a hatchway opening therethrough, and a collapsing ventilating door for said hatchway adapted, in its open position, to occupy a space between said hatchway and the adjacent end wall of the car. 80
5. In combination, a railroad refrigerator car comprising a roof having a hatchway opening therethrough, and a ventilating door for said hatchway constructed of pivoted links adapted to collapse into a space between said hatchway and the adjacent end wall of the car. 85
6. In a railroad car comprising a roof having a hatchway therein, a ventilating door for said hatchway comprising a series of lazy tong links folding into a space to one side of said hatchway. 90
7. In a railroad car comprising a roof having a hatchway, a pair of guide members extending along margins of said hatchway, and a folding ventilating door movable in said guide members. 95
8. In combination, a railroad refrigerator car comprising a roof having a hatchway, parallel guide channels extending adjacent the edges of said hatchway at the bottom thereof, and a collapsing ventilating door slidable in said guide channels. 100
9. In combination, a railroad car comprising a roof having a hatchway therein spaced from the adjacent end wall of the car, and a door movably supported at the lower end of said hatchway to close said hatchway or to lie wholly between said hatchway and the adjacent end wall of the car. 105
10. In combination, a railroad car comprising a roof having a hatchway therein spaced from the adjacent end wall of the car, a sliding ventilating door movable in a plane at the lower end of said hatchway, and guide means for said door extending from said hatchway to the adjacent end wall of the car, whereby said sliding ventilating door has movement to close said hatchway or to lie wholly between the edge of said
- hatchway and the adjacent end wall of the car. 110
11. In combination, a railroad car comprising a roof having a hatchway therein spaced from the adjacent end wall of the car, and a door for said hatchway adapted in one position to close said hatchway and in another position to lie wholly between said hatchway and the adjacent end wall of the car. 115
12. In combination, a railroad car comprising a roof having a hatchway movable in a plane at the lower end of said hatchway for closing said hatchway, and co-operating locking devices in said hatchway and on said door for locking said door in closed position, said locking devices being accessible through the top of said hatchway. 120
13. In combination, a railroad car comprising a roof having a hatchway spaced from the adjacent end wall of the car, a pair of guides supported in said car at the lower end of said hatchway and extending substantially to said end wall, a ventilating door movably supported in said guides to close said hatchway or to lie wholly between said hatchway and the adjacent end wall of the car, and co-operating locking devices in the hatchway and on the edge of said door for locking said door in closed position, said locking devices being accessible through the top of said hatchway. 125
14. In combination, a railroad car comprising a roof having a hatchway therein, and a collapsing door for said hatchway comprising a plurality of articulated links, said links being of angle bar section with opposing flange surfaces contacting at the points of articulation of said links, and pivot pins passing through the contacting flanges. 130
15. In combination, a railroad car comprising a roof having a hatchway therein, a folding ventilating door for closing said hatchway at its lower end, said door comprising a plurality of articulated links, a stationary attaching member secured to said car, said attaching member having a slot therein extending in a plane at right angles to the plane of folding movement of the door, and a projection on one of said links sliding in said slot and serving to attach said door to said attaching member. 135
16. In combination, a railroad car comprising a roof having a hatchway therein, a folding ventilating door for closing said hatchway, said door comprising a plurality of links pivoted together, a bar defining the free edge of said door, said bar having longitudinal slots therein, and pins on the end links of said door engaging in said slots. 140

In witness whereof, I hereunto subscribe my name this 9th day of December, 1924.

GEORGE A. HULL.
